[57] **CLAIM**

The ornamental design for a housing for a apparatus
for cleaning soldering iron tips, as shown and described.

DESCRIPTION

FIG. 1 is a front perspective view of a housing for an
apparatus for cleaning soldering iron tips showing my
new design;

FIG. 2 is a front view thereof;

FIG. 3 is a rear view thereof;

FIG. 4 is a side view thereof, the opposite side being the
mirror image of the side shown;

FIG. 5 is a top plan view thereof; and

FIG. 6 is a bottom plan view thereof.

FIG. 1

FIG. 2

FIG. 3

FIG. 4
